(57) CLAIM

The ornamental design for a remote controller for air conditioner, as shown and described.

DESCRIPTION

FIG. 1 is a top plan view of the remote controller for air conditioner showing our new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a cross-sectional view taken along line A-A' of FIG. 3 where internal mechanism was omitted.

1 Claim, 2 Drawing Sheets

FIG. 1.FIG. 2.FIG. 3.FIG. 4.FIG. 5.FIG. 6.FIG. 7.
